(57) **CLAIM**

The ornamental design for a combined microphone and phone holder for music sheet stand, as shown and described.

DESCRIPTION

FIG. 1 is a front perspective view of a combined microphone and phone holder for music sheet stand showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the combined microphone and phone holder for music sheet stand; and, FIG. 10 is an enlarged detailed view of the encircled area 10 shown in FIG. 1.

The dash-dash broken lines in the drawings depict portions of the combined microphone and phone holder for music sheet stand that form no part of the claimed design. The dot-dash broken lines represent boundaries of the enlarged portion and form no part of the claimed design.
